UNITED STATES PATENT OFFICE.

WALTER I. MAYER AND FREDRICK BEAGLE, OF KANSAS CITY, MISSOURI, ASSIGNEES
TO THE VICTORY ADVERTISING MANUFACTURING COMPANY, OF KANSAS CITY,
MISSOURI, A CORPORATION OF MISSOURI.

DISPLAY DEVICE.

1,399,783.

Specification of Letters Patent. Patented Dec. 13, 1921.

Application filed March 3, 1921. Serial No. 449,587.

To all whom it may concern:

Be it known that we, WALTER I. MAYER and FREDRICK BEAGLE, citizens of the United States, residing at Kansas City, in the

5 county of Jackson and State of Missouri, have invented certain new and useful Improvements in Display Devices; and we do declare the following to be a full, clear, and exact description of the invention, such as 10 will enable others skilled in the art to which it appertains to make and use the same, reference being had to the accompanying drawings, and to the letters and figures of reference marked thereon, which form a 15 part of this specification.

This invention relates to a display or advertising device and particularly to a device which may be conveniently located in a display window upon a counter or upon a 20 table, the device being so constructed that it will mechanically bring into view different objects preferably at uniformly divided stages or periods and when the end of the sequence of operations has been reached, 25 the device is so constructed that the displayed objects will be re-displayed in reverse order. For example, the devices to be displayed or the matter to be displayed, as the case may be, may be arranged on 30 leaves or panels which may be moved one after the other intermittently in one direction, for example, from right to left, until all of the leaves of panels have been operated; then the last leaf or panel will 35 be the first one moved from left to right in reverse order. This alternating relation of movement will continue so long as power is applied to the mechanism for operating the leaves or panels.

40 The novel construction of the invention as well as the means of operation, will become apparent by reference to the following description in connection with the accompanying drawings, in which—

45 Figure 1 is a perspective view of a display device constructed in accordance with our invention.

Fig. 2 is a rear perspective view of the device showing the operating mechanism, 50 the rear wall of the case being removed.

Fig. 3 is a vertical, longitudinal, sectional view through the device.

Fig. 4 is an edge elevational view of the operating gearing.

Fig. 5 is an enlarged plan view of the 55 leaf turners, and

Fig. 6 is a cross sectional view through the leaf turners.

Referring now to the drawings by numerals of reference:

1 designates the base of a case having a front panel 2, end walls 3 and 4 and a removable rear panel 5. On the base 1 is a gearing supporting frame consisting of the two plates 6 and 7, fastened to the base 1 and provided with bearings for certain of the shafts which support the transmission gears. The base also carries an electro-motor 8, on the drive shaft of which is a pulley 9 driving a pulley 10 on the shaft 11 65 through the medium of the belt 12. The shaft 11 is mounted in bearings in the respective plates 6 and 7 and said shaft carries a pinion 13, which meshes with a gear 14 on the shaft 15, mounted in the plates 75 6 and 7. The shaft 15 carries a pinion 16, which meshes with a gear 17 on the shaft 18, also supported by the plates 6 and 7 and on the shaft 18 is a pinion 19 which meshes with a gear 20 on shaft 21 carried by the 80 plates 6 and 7. The shaft 21 has a cup-shaped coupling 22, provided with a slot 23 therein to be engaged by a pin or transverse projection 24 on a disk-operating shaft 25 in a bearing arm 26, carried by the plate 6. 85

The gearing just described affords considerable reduction in speed between the motor shaft and the disk 27 rigid on the shaft 25; therefore, the motor may operate at relatively high speed while the disk or 90 head 27 will rotate at relatively low speed.

The disk 27 is the leaf turner actuator and it cooperates with the leaf turning mechanism in front of the casing.

The leaf turning mechanism is shown as 95 consisting of two shafts 28 and 29. The shaft 28 is provided with a plurality of mutilated gears or disks at the upper end, there being four shown and designated 30, 31, 32 and 33 respectively. These disks 100 are loose on the shaft 28 and their toothed portions 34 mesh with the toothed portions 35 of complementary disks 36, 37, 38 and 39 for the disks 30, 31, 32 and 33 respectively.

Each disk or mutilated gear is provided 105 with an outstanding, laterally projecting arm or finger 40, to be engaged by an actuating arm or finger 41 on the leaf turner.

actuator or disk 27. The number of fingers or arms 41 on member 27 will correspond to the number of arms 40 to be actuated and the arms 41 will be of progressively increasing lengths so that the first arm for the finger 40 on the disk 33 will be long enough to contact with the finger on disk 33 but will be too short to contact with the finger on disk 32. The next arm 41 will be long enough to contact with the finger 40 on disk 32 but not long enough to contact with the finger on disk 31, the next arm 41 being long enough to contact with the finger 40 on disk 30. Therefore, as the disk or head 27 rotates, the fingers 41 will progressively engage the fingers 40 on the respective disks or mutilated gears to turn the disks 39, 38, 37 and 36 in sequence.

The disks 36, 37, 38 and 39 carry fingers 42, 43, 44 and 45 respectively, having grooved portions to support the panels or leaves 46, 47, 48 and 49. Therefore, as each mutilated gear or disk carrying an arm 40 is turned, a corresponding movement will be imparted to its complementary leaf-carrying disk so that the leaves will be folded over from right to left until all of the leaves have been turned.

When all of the leaves have been turned, the last arm or finger 41 will have passed the fingers 40 and the arms 41 will be carried to the lower portion of the casing to engage corresponding fingers 40' on a set of mutilated gears, generically designated 50, which engage complementary leaf-turning disks, the group being generically designated 51. Since the groups at the bottom correspond in detail to the groups at the top, as the arms 41 contact with those designated 40' at the bottom, the reverse order of movement of the leaves will take place, as will be well understood, the leaves being progressively turned until all of them have been restored to their original position, after which the arm or finger 41 will have moved to the top to again turn them from right to left. The alternating sequences will be continued so long as the device is operated.

The motor may receive power from any suitable source as, for example, a commercial circuit, and I have shown a plug 52 carrying conductors 53 and 54. The conductor 53 is connected to a switch 55, whereby the circuit may be broken. The conductor 53 is also connected to lamps 56 and 57, the conductor 54 being interrupted by insulated contacts 58, adapted to be bridged by the spaced conductor plates 59 in the back of the disk or head 27, as will be clearly seen in Fig. 2. Therefore, as the disk rotates, the light circuit will be intermittently closed and opened to flash the lights intermittently, the contacts being arranged so that the light will be flashed on when the leaf has been turned and flashed off while the leaf is turn-

ing. The motor is connected to the circuit consisting of the conductors 53 and 54 in parallel, as shown in Fig. 2, and there is preferably a rheostat 60 for controlling the speed of the motor.

The circuit wiring is not important as any means can be utilized for flashing on the light at such times and at such periods as desirable, the essential novelty of the invention residing rather in the mechanism for operating the panels of leaves.

The mutilated disks or gears on the respective shafts 28 and 29 may be mounted in any convenient manner and are preferably spaced apart by spacing washers or collars 61 and 62.

It is apparent, of course, that the removable panel 5 in the back of the machine may be secured in any convenient manner and it is adapted to be taken out in order that access to the interior of the case may be had whereby inspection or repairs to the mechanism may be made.

Attention is called to the fact that the arms 40' for the leaf-turning elements at the bottom of the shaft 29 are offset with respect to the arms 40 at the top, this being desirable because when the leaves have been turned over in one direction, it is necessary to have the arms for the lower leaf-turning elements in line with the pins 41 when they reach the bottom of the casing so that they may come in contact with the arms 41 to turn the leaves back to their original position.

It is necessary to offset the arms 40' for the lower leaf-turning elements with respect to the arms 40 because in the initial operation of the machine when a pin on the turned head contacts with the arm 40, it will impart a partial rotation to one of the upper disks and correspondingly turn the leaf-supporting element, in turn giving a partial rotation to one of the leaf-turning elements at the bottom of the casing and since the leaf-turning elements at the bottom of the casing are in mesh with the mutilated gears of the set 51, there will be a corresponding turning movement imparted to that set of mutilated gears. If the arms 40' are not offset with respect to the arms 40, they would be moved out of the path of the fingers 41. By offsetting the arms 40 and 40' with respect to each other, there will always be one set of arms in the path of movement of the fingers.

What we claim and desire to secure by Letters-Patent is:

1. In a device of the class described, a plurality of independently movable panel-carrying gears, complementary gears meshing therewith and having laterally projecting arms, a selective disk having fingers to selectively contact with the arms on the complementary gears, and move them to

progressively turn the panels, and means for actuating said disk.

2. In a device of the class described, a plurality of leaf-supporting, rotating elements having independent movement, complementary elements in direct driving connection therewith and having lateral arms normally arranged in vertical alinement, a rotatable head at right angles thereto and having selective arms of different lengths to progressively engage the arms on the complementary elements from the bottom toward the top, and means for actuating said head.
- 15 3. In a device of the class described, a plurality of leaf-supporting, rotating elements having independent movement, complementary elements in direct driving connection therewith and having lateral arms normally arranged in vertical alinement, a rotatable head at right angles thereto and having selective arms of different lengths to progressively engage the arms on the complementary elements from the bottom toward the top, means for actuating said head, and leaf-reversing devices to be engaged by the arms on the head after all of the leaves have been turned in one direction so that the leaves will be progressively 25 returned in the opposite direction.
- 20 4. In a device of the class described, a casing, a pair of shafts in substantially vertical parallel planes mounted in the casing,

sets of leaf-turning elements loose on one of the shafts, sets of leaf-turning disks 35 loosely mounted on the other shaft, the disks having laterally projecting arms, a rotating head substantially at right angles to the arms and having fingers for progressively engaging the arms on the disks, means 40 for actuating the head to contact with the arms so as to turn the leaves progressively in one direction, and sets of complementary leaf-turning elements and disks at the opposite end of the shaft to be engaged by 45 the fingers to turn the leaves in an opposite direction when the turning sequence has been completed through the first named devices.

5. In a device of the class described, a 50 casing, a gear frame in the casing, a constantly driven shaft carried by the gear frame and having a cup-shaped head provided with a slot, a shaft at an angle thereto and having a projection engaging said 55 slot, a head on the end of the shaft, projecting fingers of progressively increasing lengths on the perimeter of the head, a plurality of disks having laterally projecting arms in the path of the fingers, and rotatable leaf-supports in driving connection with said disks.

In testimony whereof we affix our signatures.

WALTER I. MAYER.
FREDRICK BEAGLE.
